UNITED STATES PATENT OFFICE.

HENRY M. CROWELL, OF MAPLEWOOD, NEW JERSEY.

HYDRAULIC ROCKING PRESS.

SPECIFICATION forming part of Letters Patent No. 634,719, dated October 10, 1899.

Application filed April 22, 1899. Serial No. 714,039. (No model.)

To all whom it may concern:

Be it known that I, HENRY M. CROWELL, a citizen of the United States, residing at Maplewood, in the county of Essex and State of

5 New Jersey, have invented certain new and useful Improvements in Hydraulic Rocking Presses; and I do hereby declare the following to be a full, clear, and exact description of the invention, such as will enable others 10 skilled in the art to which it appertains to make and use the same, reference being had to the accompanying drawings, and to letters of reference marked thereon, which form a part of this specification.

15 The object of this invention is to secure a more perfectly defined and artistic and ornamental impression, more particularly upon sheet metal, whereby the design will be better defined by mere die-work than heretofore, 20 the invention applying more particularly to the construction and ornamentation of articles made of thin silver or other metal for jewelry, tableware, handles, clasps, buckles, and the like.

25 A further object is to facilitate the work of thus striking up or raising articles of sheet metal, to secure a more perfectly automatic operation, and to obtain other advantages and results, some of which may be referred to hereinafter in connection with the description of 30 the working parts.

The invention consists in the improved press for operating dies and in the arrangements and combinations of parts thereof, all 35 substantially as will be hereinafter set forth, and finally embraced in the clauses of the claim.

Referring to the accompanying drawings, in which like letters of reference indicate corresponding parts in each of the several views, Figure 1 is a front elevation of a press of my improved construction, one of the upper shafts of which is in section. Fig. 2 is a side elevation of the same, another shaft being 45 in section and a fly-wheel thereon removed. Fig. 3 is a side elevation of a certain force-carrier. Fig. 4 is a section of the same, taken on line x. Fig. 5 is a sectional detail of a slotted bushing which will be hereinafter 50 more fully described. Fig. 6 is a detail showing the base of the press; and Fig. 7 is a sec-

tion of the same on line y, showing certain hydraulic devices useful in operating the die-holder more clearly.

In said drawings, *a* indicates a suitable bed-frame of heavy metal, which may be of one integral piece or in separable sections. In the preferred construction, for convenience of manufacture, I prefer to have the bed-plate *a*², which carries the press proper, of a 55 separate piece from that portion *a*¹ which carries the hydraulic pumps and co-operating devices. Upon said frame is arranged a base-piece *b*, (shown more clearly in Figs. 2, 6, and 7,) which is centrally cored out and forms a 60 cylinder for a die-holder *c*, the said die-holder at its lower end being also cylindrical to fit the chamber within the base *b* and form a piston adapted to be operated upon by hydraulic influences, as hereinafter described. 65 The top of the said die-holder *c* is arranged in connection with guides *d* or other steady-ing means and is provided at the center of its upper end with a seat *c'* for the die *r*. This 70 said seat may be of any suitable construc-tion, means being provided for holding said die in place, such as a set screw or screws *e*. Upon the said guides *d* is seated near the upper ends thereof a cross-head *f*, the said cross-head being perforated to receive the bolt-like 75 upper extensions *d'* of said guides, said guides being flanged, as at *g*, to provide seats for the said cross-heads and being provided with nuts *h*, by means of which the said cross-head is firmly and rigidly held in place. The guides 80 *d* thus serve as supporting-pillars for said cross-heads, and four of such pillars are pref-erably employed, which provide openings be-tween at all sides of the press, so that the 85 metal to be stamped or impressed may be fed to the die and force by automatic ma-chinery or by hand from either direction. The said cross-head *f* provides bearings for parallel shafts *i* and *j*, the latter extending out at one side from the cross-head to receive 90 a pulley and balance-wheel *k*. Upon the upper shaft *i*, within a chamber or aperture formed within the cross-head, is arranged an oscillat-ing arm *l*, which extends downward to the second shaft *j* and is there provided with an 95 opening for said shaft *j* and a bushing *m*, ar-ranged around said shaft. The said bushing 100

m is provided with a slot *m'*, Figs. 4 and 5, and the said shaft *j* where it lies in said bushing is eccentrically reduced, the eccentric pin or part *j'* of said shaft fitting the slot *m'* of 5 the bushing *m*, so that when said shaft *j* rotates in its bearings in the cross-head the said bushing *m* will be given a reciprocating motion in connection with the arm *l*. Upon the said bushing *m*, in connection with the arm 10 *l*, is arranged a force-carrying arm *n*, which is also at its upper end given a similar oscillatory action with the bushing. The lower end of the said force-carrier *n* is guided to a proper central or approximately central relation to the die by guiding-springs *o o*, which engage suitable coöperating guides *p*, so that the lower end of the force-carrier *n* and its force *q* will be brought with sufficient exactness into coöperating relation to the die *r*.

20 The force *q* is provided with a suitable metal face serving to coöperate with an engraved or otherwise shaped face of the die *r*, the force serving to press the metal into said die and in the act of forcing it to rock upon the face 25 of said die in such a manner as to cause the metal to flow into place by a swaging or burnishing action rather than by a straight pressure, as heretofore.

The pulley *k* and shaft *j* are rotated at a 30 high rate of speed, so that at each upward action of the die the said force will be given several rocking actions or reciprocations upon the upper face of the metal lying on the die.

The action of the force causes the metal to 35 creep into the hollows and recesses of the die, so that by a single reciprocation of the piston the metal is raised or impressed, effecting very marked elevations and depressions in the sheet metal, conducing to a high grade of or 40 namentation.

To secure a high pressure and quick action of the die to and from the force, whereby the above results are accomplished with greater facility and without stress upon the workmen, 45 I have operated the said die by hydraulic power, and to this end, in connection with the cylindrical base *b* and piston *c* of the die-carrier, I have employed a cylinder-head *b'*, closing the lower end of the cylindrical chamber 50 in said base, the said head *b'* being provided with inlet and outlet ports *b²* *b³* or passages which are in connection with water-supply and return pipes *s s*, connecting with a hydraulic pump *t*, carried upon the base portion 55 or section *a'* of the frame *a*.

The hydraulic pump employed is of any suitable construction common in the market, and the details of the same need not necessarily be described here. The said pump *t* is provided with a safety-valve *t'*, adapted to be regulated by means of a regulating-screw *t²* or other suitable means, by means of which I am enabled to regulate the hydraulic pressure within the cylindrical base. By means 65 of this safety device I am enabled to maintain pressure upon the sheet metal at any desired degree, and should the pressure increase

above the proper normal the safety device will automatically act in any ordinary manner to allow the escape of water. Thus when 70 I employ stock which is of a more or less brittle nature I can reduce the pressure and give the work more time in rolling to effect the desired end, and when employing a more tenacious material the power can be increased and 75 the work facilitated.

When the machine is at rest, the pipes *s s* are in open communication through the cylinder-chamber. When I desire to raise the piston and its die to the force, I close communication through the return-pipes *s'* by means of a valve *s²*, having the arm or lever *s³*, so that the water rises in the cylinder and forces the die-carriers upward and the die into operative relation to the force. This 85 valve is preferably operated by a treadle *u*, (shown more clearly in Fig. 2,) the said treadle being connected to the arm *s³* by a connecting-rod *u'* or in any other suitable manner.

To enable the force to effect the desired 90 rocking movement on the face of the die, the impression-surface thereof is not the exact counterpart of the engraved or sunken surface of the die. The said impression-surface is made while the force is of comparatively 95 soft metal by rocking the force on the face of the die. I thus obtain a somewhat-distorted negative of the positive die and am enabled to rock the force reciprocally over the face of the die when subsequently stamping the sheet 100 metal in the same manner as when preparing the force.

Thus constructed when stamping or impressing the sheet metal but one part of the 105 rocking force will be in hard engagement with the die at a time, like as one part of an ordinary rocker of a rocking-chair engages the floor at a time, and the power due to the impression of the die being brought upon but a small portion of the surface of the metal to 110 be impressed at a time the desired flow of the metal into the sunken recesses of the engraving is secured at but a comparatively small expenditure of power.

Having thus described the invention, what 115 I claim as new is—

1. The combination with a vertically-reciprocating die, of a jointed force-carrier and means for oscillating the sections at the joint, a force having a rocking motion due to the 120 action of the said carrier, and operating means for the die, substantially as set forth.

2. The improved press, comprising a bed-plate *a*, base-piece *b*, having a water-chamber, a pump for forcing fluid into said chamber, a piston *c*, having a die *r*, seated thereon, pillars *d*, *d*, cross-head *f*, having shafts *i*, and *j*, the latter having an eccentric portion, a slotted bushing and pulley, an arm *l*, carried by the shaft *i*, and providing bearings for said bushing, an arm *n*, carried by said bushing and at its lower end having a force, all said parts being arranged and operating, substantially as set forth.

3. The improved press, comprising a bed-
plate, chambered base-piece, pump for forc-
ing water into the chamber of said base-piece,
a piston, a die seated thereon, pillars, sup-
porting a cross-head, shafts *i*, and *j*, the lat-
ter having an eccentric portion, a slotted bush-
ing and a pulley, an arm *l*, carried by the
shaft *i*, and providing bearings for said bush-
ing; an arm *u*, carried by said bushing and
carrying a force to coöperate with the die, and
centering means for bringing the force into
proper relation to the die substantially as set
forth.

4. The improved press for ornamenting
sheet metal, which comprises a bed, a force
and its carrier having jointed arms or sec-
tions, an eccentric arranged at the joint in
said carrier, and means for operating the said
arms, and a die coöperating with said force

to ornament the metal, substantially as set 20
forth.

5. The improved press for ornamenting
sheet metal, comprising a cylindrical bed, a
die seated upon a piston, in said cylindrical
bed, hydraulic apparatus for raising and low- 25
ering said piston, a jointed force-carrier,
means for operating the same at the joint to
effect a rocking movement of the force, and
said force adapted to coöperate with the die
to ornament the metal and rock thereon re- 30
ciprocally, substantially as set forth.

In testimony that I claim the foregoing I
have hereunto set my hand this 17th day of
April, 1899.

HENRY M. CROWELL.
